UNITED STATES PATENT OFFICE.

ANDREW C. ZENORINI, OF WEST HOBOKEN, NEW JERSEY.

THREAD-CONTROLLING MECHANISM FOR EMBROIDERY-MACHINES.

1,288,369.

Specification of Letters Patent.

Patented Dec. 17, 1918.

Application filed February 11, 1916. Serial No. 77,740.

To all whom it may concern:

Be it known that I, ANDREW C. ZENORINI, a subject of the King of Italy, and a resident of West Hoboken, in the county of 5 Hudson and State of New Jersey, have invented certain new and useful Improvements in Thread-Controlling Mechanism for Embroidery-Machines, of which the following is a specification.

10 This invention relates to improvements in thread-controlling mechanism for embroidery machines.

By the use of my invention I produce a tensioning lock bar having a guide for each 15 thread and provided with means adapted alternately to grip and release each individual thread or end, whereby each individual thread may be fed and tensioned to the embroidery implements independently 20 but without separate manipulation so that when one series of needles are thrown into operation or operative position and another series are thrown out of operation or into reserved position, the operating series may 25 be fed without unthreading the reserve needles and without separately manipulating a series of locking or friction disks. Furthermore each individual end or thread will be guided and retained in its proper position 30 relatively to its neighbors irrespective of the position or planes of movement of the working implements through which the particular thread is being fed.

Another feature of my invention is the 35 provision in lock bars of the type herein described of means for preventing the crushing of the reserved or stationary threads by the repeated operation of the locking bar thereon during its movement to alternately 40 grip and release the moving threads which are being fed to the needles.

Another feature of my invention is the provision intermediate the embroidering implements and the locking bar of a plurality of take-up bars adapted to be simultaneously moved toward and away from each other to alternately take-up and loosen the thread, each of which bars is provided with a series of vertical anti-tangling 45 flanges separated by a series of elongated vertical slots whereby a separate or independent guide groove for each individual thread or end is provided, so as to retain each individual thread in suitably spaced 50 relation from its neighbor to prevent the tangling of the threads which in devices of

the type hereinbefore referred to would be likely to occur in view of the great number of threads or ends employed.

Furthermore, I preferably provide at the 60 head of each elongated vertical slot a hair spring so arranged as to permit the easy entrance of a thread into said slot but to retain the same therein and prevent accidental slipping out of said thread there- 65 from during the loosening of the thread by such tensioning bars.

In the accompanying drawings in which similar reference characters designate corresponding parts throughout the several 70 views,

Figure 1 is a rear elevation partially broken away of a thread locking device and operating parts included in my invention;

Fig. 2 is a plan view partially broken 75 away of said thread locking device;

Fig. 3 is a front elevation partly broken away of said device;

Fig. 4 is a section on the line 4—4 of Fig. 1, illustrating the thread locking or 80 thread gripping position of the component bars of said thread locking device;

Fig. 5 is a section similar to Fig. 4, illustrating the unlocked position of the component bars of said device;

Fig. 6 is a section on the line 6—6 of Fig. 1 and also illustrates my improved 85 anti-tangling take-up bar;

Fig. 7 is a side elevation of one of the take-up bars shown in Fig. 6.

Referring now to these drawings which illustrate a preferred embodiment of my invention, 1 indicates a base or table bar, preferably stationary, and supported in any suitable way from the frame of the machine 95 and 2 indicates a bar preferably composite in structure, movable in relation to the bar 1 and preferably reciprocating vertically in relation to the base or table bar 1 as hereinafter described. The said bar 2, as shown, 100 is composed of an actuating bar 3 connected at opposite ends by straps 3^b to plungers 14, which plungers are suitably mounted in bearings 15, and is raised by contact with eccentric cams 16 mounted on a shaft 17 ex- 105 tending parallel to said plate and rotated from any suitable source of power not shown. Said plunger is retained in contact with said cams 16 by springs 17^a, which abut at one end against the stationary bearing 15 110 and at the other end against any suitable abutment (not shown) on the plunger 14.

To the bar 3 is suitably secured a bar 4 having an alining flange 4^a along its lower marginal edge and said bars 3 and 4 being secured together by screws 5 or in any other suitable manner. The bar 3 is provided throughout its length with a series of thread guiding slots 3^a dividing the upper half of said bar into what I shall term sections 3^c, and the bar 4 is provided with a series of alternate openings 4^b and upward extensions 4^c, the extensions 4^c extending upwardly above the bar 3 and abutting against alternate sections 3^c of the bar 3. Said bar 4 is also provided with a series of horizontally disposed blocks 6 mounted at the upper edge thereof and suitably supported by webs 7. Said abutting blocks 6 extend forwardly to overhang the bar 1 and extend laterally on opposite sides of the web 7 so as to overhang slots 3^a—3^a on opposite sides of the web 7 and are so disposed in relation to each other as to form thread channels 8 between contiguous blocks.

To the under surface of each of such blocks is secured two pairs of springs 9 and 10 respectively which are secured to said block 6 in vertical alinement with the slots 3^a by means of screws 11 or in any other suitable manner. Obviously, if a thread is passed downwardly through the channels 8 and thence moved horizontally under one end of the block 6 and into a slot 3^a it may be positioned directly beneath springs 9 and 10 and if the bar 3 is reciprocated vertically in relation to the bar 1 the pressure will be alternately relieved from and applied to the springs 9 and 10 which will be caused to alternately grip and release the thread 12.

The spring 10 is preferably made of thinner metal and more resilient than the spring 9 and is, when the bars 1 and 3 are separated, so bent as to press with a yielding pressure upon the thread 12 and the spring 9 is disposed in alinement above said spring 10 so that when the bar 3 is moved downwardly in relation to the bar 1 it will cause the thread gripping pressure to be gradually though firmly applied to the spring 10 and through it to the thread 12, whereby all chopping or crushing of the thread fiber is prevented while at the same time the thread is alternately securely gripped so as to securely lock the thread against movement and yieldingly retained so as to permit the feeding of so much only of said thread as is drawn through the locking device by the tensioning device, and this result is accomplished even though a predetermined part of the thread be retained in stationary position within said locking device for a considerable period of time as is the case in embroidering machines where different colored threads are being employed and in which one or more series of threads may be thrown out of operation while other series

of threads are in operation or being fed to the embroidering implements.

In Figs. 6 and 7 I have shown my combined locking and yielding tensioning device in combination with novel take-up bars 70 which are mounted as shown to rock simultaneously toward each other to loosen the thread so as to permit feeding and simultaneous rocking in the opposite direction to take up the thread. These take-up bars are of similar construction and each of them comprises vertical arms 18 at opposite ends of and suitably secured upon a horizontal shaft 19 by means of collars 18^a. The arms 18 at their upper end are provided with collars or sockets 18^a into which is fitted a cylindrical bar 20 which is provided with a series of vertically extending flanges 21 so disposed in relation to each other as to provide elongated thread slots 22 therebetween 85 and each flange has suitably secured thereto as with screws 24 a hair spring 23 which extends laterally and closes the top of a slot 22. These hair springs are so inclined and bent as to permit the ready entrance of a thread into a slot 22 but to prevent the accidental slipping out of such thread when so inserted.

It will be obvious that the springs 9 and 10 coöperate not only to prevent the crushing of the thread and the alternate gripping and releasing thereof by the locking bars but also prevents a tangling due to the over-feeding of thread through the locking device.

Having described my invention, I claim: 100
 1. A locking and tensioning device for embroidery machines embodying two relatively vertically movable members extending horizontally and adapted to separate and close together, a flat spring mounted on one of said members in registry with each thread and adapted to gradually transmit the closing pressure of said movable members to the thread.

2. A locking and tensioning device for embroidery machines embodying two relatively vertically movable members extending horizontally and adapted to separate and close together, a flat spring in registry with each thread and connected at one end with one of said movable members and free at its opposite end, the said flat spring being adapted to gradually transmit the closing pressure of said movable members to the thread. 110

3. A locking and tensioning device for embroidery machines embodying two members adapted to separate and close together, means for guiding a series of threads through such members and springs connected to one of said members in alinement with said thread guiding means and yieldingly pressing against the other member to provide a yielding tension on the threads while the bars are separated and to prevent crushing of the threads upon the closing of said bars. 125

4. Locking and tensioning devices for embroidery machines embodying a stationary member and a member movable into and out of thread pressing relationship with said stationary member, the said members extending horizontally and one of the same being provided with thread-guiding slots, a series of springs in alinement with said thread guiding slots and mounted on said movable member to prevent crushing of the threads upon the closing movement of said members. 10
5. Locking and tensioning devices for embroidery machines embodying a stationary member and a member movable into and out of thread-pressing relationship with said stationary member, the said members extending horizontally and one of the same being provided with thread-guiding slots, and a series of springs mounted on the movable member in alinement with the thread guiding slots and yieldingly pressing against the stationary member when the movable and stationary members are out of thread-pressing relationship, as and for the purpose specified. 25
6. Locking and tensioning devices for embroidery machines embodying a stationary member and a member movable into and out of thread-pressing relationship with said stationary member, the said members extending horizontally and one of the same being provided with thread-guiding slots, a series of springs mounted on the movable member in alinement with the thread guiding slots and yieldingly pressing against the stationary member and another spring registering with the first mentioned spring to cause the closing pressure of the movable member to be more gradually applied to said first mentioned spring and through it to the thread. 35
7. A locking and tensioning device for embroidery machines embodying therein a table member retained in stationary position and a vertically movable member having an overhanging part, the said members extending horizontally and one of the same being provided with thread-guiding slots, means for moving said overhanging part alternately into and out of thread-pressing relationship with said table member and a series of springs secured to said overhanging part in alinement with said thread slots. 45
8. A locking and tensioning device for embroidery machines embodying therein a table member retained in stationary position and a vertically movable member having an overhanging part, the said members extending horizontally and one of the same being
- provided with thread-guiding slots, means for moving said overhanging part alternately into and out of thread-pressing relationship with said table member, a series of springs secured to said overhanging part in alinement with said thread slots and yieldingly pressing against said stationary member when the members are in separated position. 60
9. A locking and tensioning device for embroidery machines embodying two horizontally-disposed and vertically movable members adapted to separate and close together, means for guiding a series of threads through such members and a take-up member having a series of upstanding anti-tangling flanges separated by a series of elongated vertically extending slots. 65
10. A locking and tensioning device for embroidery machines embodying two horizontally-disposed and vertically movable members adapted to separate and close together, means for guiding a series of threads through such members, a take-up member having a series of upstanding anti-tangling flanges separated by a series of elongated vertically extending slots and a series of yielding springs arranged to close the tops of said slots to retain the threads therein against accidental displacement. 70
11. A locking and tensioning device for embroidery machines embodying therein a table member retained in stationary position and a vertically movable member having an overhanging part, the said members extending horizontally and one of the same being provided with thread-guiding slots; means for moving said overhanging part alternately into and out of thread-pressing relationship with said table member and a series of springs secured to said overhanging part in alinement with said thread slots and yieldingly pressing against said stationary member when the members are in separated position. 75
- In testimony whereof, I have signed my name to the foregoing specification in the presence of two subscribing witnesses. 80
